UNITED STATES PATENT OFFICE.

WILLIAM L. COLESTOCK, OF PHILADELPHIA, PENNSYLVANIA.

DELIVERING MECHANISM FOR PHONOGRAPHIC RECORD CABINETS.

Application filed February 25, 1926. Serial No. 90,549.

This invention relates to phonographic record cabinets or holders for phonographic records, and particularly to means whereby the records may be delivered one at a time by depressing a key or like operating device.

A further object is to provide a device of this character which is very simple, which can be easily applied to any make of record cabinet, which permits the ready placement 10 of the records within the cabinet and whereby any one record desired may be quickly and easily discharged from the cabinet without affecting any other adjacent records.

Other objects will appear in the course of 15 the following description.

My invention is illustrated in the accompanying drawings, wherein:—

Figure 1 is a front elevation of a phonographic record cabinet constructed in accordance with my invention;

Figure 2 is an enlarged vertical section from front to rear through the lower portion of the cabinet;

Figure 3 is a section on the line 3—3 of 25 Figure 2;

Figure 4 is a fragmentary enlarged sectional view through the web 15, showing in elevation one of the lifters and the actuating means therefor;

Figure 5 is a fragmentary vertical section 30 through the forward edge of the web 15;

Figure 6 is an end view of the button 23;

Figure 7 is a section on the line 7—7 of 35 Figure 3;

Figure 8 is a section on the line 8—8 of Figure 2;

Referring to these drawings, it will be seen I have illustrated an ordinary record cabinet, designated A, having the usual form 40 and provided with an upper compartment (not illustrated) wherein the phonographic reproducing mechanism is disposed, and a lower compartment, designated generally 10, wherein the records are designed to be kept, this lower compartment being closed by the two doors 11. As illustrated in Figure 2, the forward end of the lower compartment has extending transversely across it the supporting member 12 which is upwardly flanged, 45 as at 13. Disposed against the back of the cabinet and somewhat elevated above the member 12 is a supporting member 14.

Extending from the flange 13 to the supporting member 14 is a corrugated web, 50 shown in Figure 7 and designated 15, the up-

wardly opening spaces between the downwardly opening corrugations forming tracks along which the record may roll, as later stated. Each of these tracks 16 is cut away at one point, as at 17, for a distance sufficient 60 to permit a portion of the record to project down below the tracks, as shown in Figure 2. The forward end of this web 15 is downwardly bent, as shown in Figure 5, at 18.

The web 15 just forward of the elongated 65 slots 17 is provided with downwardly projecting ears 19, to which ears are pivoted the rearwardly extending lifters 20. Each of these lifters, as illustrated in Figure 9, is somewhat T-shaped in cross section but is 70 preferably made of sheet metal so as to provide a vertical middle portion and laterally extending wings 20a. The rear end of each lifter is bifurcated to permit engagement with a vertical guide 21, there being as many 75 of these guides as there are lifters. The forward end of each of these rods 20 is pivotally connected just forward of the ears 19 to a push rod 22 which extends horizontally rearward and out through the end web 17 and is 80 there provided with a button 23, as shown in Figure 5, the face of this button being numbered or having the record otherwise indicated on it, as shown in Figure 6.

It will be obvious now that when any special rod 22 is pushed inward, it will lift upon the corresponding lifting member 20, which member bears against the downwardly projecting segment of the record, as shown in Figure 2, and this will cause the lifting of 85 this lifting member and the raising of the record up to a level with the downwardly inclined tracks 15 and 16 so that the record will roll down this track in an obvious manner and out through the front of the cabinet. The upper ends of the records are kept separate from each other by separating or partition members 24, as illustrated in Figures 1 and 2, and thus when a record rolls down the track 16 it is obvious that it will not affect in 90 any way any other adjacent record. 95

While I do not wish to be limited to any particular means for connecting the rod 22 to the lifter, I have illustrated in Figure 4 a construction wherein the rod 22 is provided at its end with an eye 25 and the arm or lifter carries a downwardly extending pin 26, the lower end of which is angularly bent and extended through the eye. Thus it will 100 be obvious that as the rod 22 is shifted rear- 105

ward, the lever 20 will be lifted and this in turn will lift the record up until it can roll down the inclined guide 16.

While I have illustrated certain details of construction and arrangement of parts, I do not wish to be limited thereto as it is obvious that many changes might be made without departing from the spirit of the invention as defined in the appended claims.

10 I claim:—

1. In a phonographic record cabinet, a plurality of downwardly and forwardly inclined tracks, each of said tracks being slotted for a predetermined distance to permit the projection of the lower margin of a phonographic record, the space above said tracks having guides separating the records from each other, a series of lifters, one for each track, and pivoted each at its forward end to the under side of the corresponding track forward of said slot, vertical guides for the rear ends of the lifters, and longitudinally shiftable rods operatively connected to the lifters forward of and below their pivotal axes, the rods extending to the forward end of the cabinet and having record indicating means.

2. In a cabinet for phonographic records, an upwardly and rearwardly incline, corrugated, transversely extending web, the corrugations of the web forming a series of downwardly and forwardly inclined tracks, the web being cut out along each track to permit the projection of the lower edge of the phonographic record through the slot thus formed, a lifter for each track pivoted at its forward end to the track just in advance of said slot, a guide for the rear end of each lifter, a longitudinally extending rod pivotally connected to each lifter rearward of its fulcrum, and a guide for the forward ends of all the rods.

3. A phonographic cabinet of the character described having therein a forwardly and downwardly extending web formed with 45 a transverse series of corrugations, the corrugations defining tracks, each of said tracks being cut out for a certain distance to form a slot through which the lower edge of the phonographic record may project, a series 50 of angular lifters, one for each track, each pivoted at its forward end beneath the track and extending rearward and adapted to bear against the lower edge of the record, guides 55 for the rear ends of the lifters, a support for the forward end of the web, said support having an upwardly inclined flange, and rods supported at their forward ends in said flange and reciprocable therethrough, the rear ends of the rods having pivotal engagement with its corresponding lifter rearward of its fulcrum.

4. A record cabinet of the character described having a series of downwardly and forwardly extending tracks, each of said 65 tracks being cut away upon its under face to permit the projection of a record, a support for the forward ends of the tracks, the support being upwardly flanged and the tracks 70 having downwardly turned ends, a record lifter for each track pivotally supported on the under side of the track forward of the slot and extending rearwardly therefrom, guides for the rear ends of the lifters, and means for vertically oscillating the lifters 75 comprising a rod for each lifter pivotally connected at its rear end thereto and passing through said downwardly turned flange on the forward end of the track, each of said rods being provided with a head, and means 80 indicating the character of the record.

In testimony whereof I hereunto affix my signature.

WILLIAM L. COLESTOCK.
